UNITED STATES PATENT OFFICE.

EDWARD P. STRODE, OF NEWARK, NEW JERSEY.

PNEUMATIC SWEEPING DEVICE.

1,149,227.

Specification of Letters Patent. Patented Aug. 10, 1915.

Application filed June 20, 1914. Serial No. 346,389.

To all whom it may concern:

Be it known that I, EDWARD P. STRODE, a citizen of the United States, and a resident of Newark, county of Essex, and State of New Jersey, have made a new and useful Invention in Pneumatic Sweeping Devices, of which the following is a specification.

My invention is directed to the application of pneumatic devices to ordinary brooms and has for its objects, first, to collect or accumulate the dust, lint or other light substances, in the act of sweeping, in a receptacle carried by the broom; second, to prevent undue circulation of dust in the air 15 through the act of sweeping.

The invention will be fully understood by referring to the accompanying drawings, in which,

Figure 1 is an edge elevational view of a common broom with my improvement applied thereto during the act of sweeping. Fig. 2 is a front elevational view of the broom in its normal condition, or when not in use, with parts broken away disclosing 25 the interior structure thereof and as seen looking at Fig. 1 from left to right. Fig. 3 is a back elevational view as seen looking at Fig. 1 from right to left. Fig. 4 is an enlarged sectional view taken through the bellows and containing box or chamber which accumulates the dust by pneumatic action. Fig. 5 is an enlarged sectional front elevational view of a part of the bellows and the dust containing box or chamber partly 35 broken away to show the interior construction of the latter. Fig. 6 is an end view of the suction nozzle as seen looking at the lower end of Figs. 2 and 3, upon the supposition that it has been removed from the 40 broom.

Referring now to the drawings and first to Figs. 1 to 3 inclusive, *b* represents the sweeping head of an ordinary broom made of bristles or broom corn and of usual form, 45 and *h* the handle secured to the broom by two levers 2 which are riveted to the handle by rivets 3 and pivotally secured to the head by a ferrule 4 through pivots 5 on each side.

6, 6' is a bellows of well known form, designed to act pneumatically to collect the dust in the dust box during the operation of sweeping, being secured at its upper end by an adjusting screw *S* to the ferrule 4, and near its center by two or more rivets or screws *s* to the head *b*. Near the center of this bellows also is a bearing 7 through

which the levers 2 slidably extend, the expansion of said bellows being limited in its movement by two pins *p*, *p* in the free or movable ends of the levers 2 and bearing 7, 60 as shown in Figs. 1 and 3.

8 is a flat metal link riveted to the lower end of the outer side 6 of the bellows and attached to a strong spiral spring 9 which is rigidly secured within the broom, as will be 65 described later on.

10 is a flat flaring suction nozzle permanently secured within the broom proper with its lower or open end relatively near the floor and between the ends of the 70 bristles or broom corn of which the broom is composed. This flaring nozzle has a long narrow suction slot *g* at its lower end (see Fig. 6) and is provided with a tubular extension 11 at its upper end adapted to be 75 inserted within a short flexible tube 13, preferably of rubber, connected in turn to a rigid metal tube 12 having connection with a dust containing box or chamber 14 secured to one face of the broom by the same screws 80 *s*, *s* which secure the inner side of the bellows thereto, or in any preferred manner, the other end of the bellows operating spring 9 being connected in turn to the rigid metal tube 12. 85

15, 15 and 17, 17 are openings in opposite sides of the dust containing box or chamber 14, and 16, 18 are two sets of flexible valves made of rubber secured to the outer and inner faces of the bellows in such manner 90 that they alternately close the openings 15, 17 as the broom is operated.

19, 19, 19 are openings on one face of the dust containing box or chamber 14 and 20 (see Figs. 4 and 5) is a piece of cheese cloth 95 or similar material of a mesh to admit of the entrance of air—but not dust or lint—into the interior of the bellows when operating.

21 is a surrounding casing for the dust 100 containing box or chamber which casing is also fixedly secured to the broom-head *b* by the screws *s*, *s*, the arrangement being such that the box 14 may be slid into and out of the surrounding casing and yieldingly held by spring 22 and a door 23 provided with locking catches 24 and 25.

The operation is as follows: The operator manipulating the broom upon the floor causes the lower end of the bristles or broom corn *b*, of which the broom is composed, to assume the position shown in Fig. 1 and this

action in turn, through the pivoted levers 2 and handle *h* causes the bellows 6 to be opened into its extended position and the bellows operating spring 9 to be put under 5 strong tension. This action, however, causes the exterior valves 16 to be closed, as shown, and in turn the valves 18 to be opened, by reason of the rigid connection of the inner portion 6' of the bellows to the broom head, 10 thereby exerting a pneumatic pumping effect upon the dust being stirred up by the bristles at the lower end and about the slot of the suction nozzle 10 and causing it, the dust, to ascend through said nozzle, through 15 the tubes 11 and 12, and into the dust containing box or chamber 14 and its surrounding casing 21 (see Fig. 4) said dust and lint ultimately settling in the box. When the broom is lifted, however, the spring 9 acts 20 under tension to restore the bellows to its normal or closed position, closing the valves 18 and opening the valves 16, thus allowing the air contained in said bellows to escape by way of the opening 15 for the valve 16. 25 After the operation of sweeping as thus described has been discontinued, the operator removes the dust box 14 from the surrounding casing 21 by releasing the catches 24 from the catches 25 of the door 23, when the dust contained in said box 14 may be 30 removed and the box again replaced in the position shown in Fig. 4 under the retaining action of the spring 22, thus keeping it firmly held in place and secure against any 35 emission of dust, except when it is desired to remove the same from the surrounding casing 21.

It will be noted that the tube 13 is sufficiently rigid to maintain its normal position 40 when the broom is not in use; in other words, it is the function of this tube to allow the suction nozzle 10 to vibrate back and forth in the act of sweeping, the spring 9 performing the actual action of restoring 45 the bellows to its normal or closed position. It will also be seen that no dust, lint or like light substances will be drawn into the bellows when the valves 18 are opened, as shown in Figs. 1, 4 and 5, because of the 50 fact that the rear side of the dust containing box or chamber 14 has numerous open-

ings 19 which are partially closed by a fabric 20 of small mesh, so that the device will be kept comparatively clean at all times. I am aware, however, that a pneumatic device, in the nature of a broom, has been devised for producing an air jet when the sweeper desires to blow the dust out of corners and other inaccessible places, but said invention is for an entirely different 60 purpose and non-analogous use, my invention being designated to distinctly avoid the circulation of dust and to collect and store the same in a receptacle carried by the broom when operated, thus preventing the annoyance and discomfort attributable to the scattering of dust and making it possible to sweep without causing any dust to lodge upon any article of furniture in the room. 65

Having thus described my invention what 70 I claim and desire to secure by Letters Patent of the United States is—

1. In combination a broom comprising a head and a handle pivotally connected thereto, a suction nozzle located in the lower end 75 of the broom, and a dust containing box or chamber operatively connected with the suction nozzle, a pneumatic pump connected with the dust box and mechanical connections between the pump and the handle of 80 the broom to operate the pump for effecting the operation of drawing the dust into the dust containing box or chamber.

2. The combination of a broom having a suction nozzle having a narrow slot located 85 within the lower end of said broom and a dust containing box or chamber carried by the broom, the suction nozzle being flexibly connected with the aforesaid box; a suction bellows and operative connections between 90 the same and the handle of the broom for causing the bellows to successively draw the dust into the box as the broom is successively operated.

In testimony whereof I have signed my 95 name to this specification in the presence of two subscribing witnesses.

EDWARD P. STRODE.
